PLATE CLAMPING MECHANISM FOR
PRINTING MACHINES

Frederick Lamatsch, Grantwood, N. J., assignor,
by mesne assignments, to R. Hoe & Co., Inc.,
New York, N. Y., a corporation of New York

Application May 25, 1934, Serial No. 727,390

9 Claims. (Cl. 101—378)

This invention relates to plate clamping mechanism for rotary printing presses, having for its object the provision of certain desired improvements in mechanism of the character indicated 5 with a view to a more convenient and efficient operation thereof.

A special object of the invention is to provide 10 a plate lockup of a design and construction particularly adapted to permit a more facile manipulation of a plate clip while permitting the attainment of a narrow margin or space between adjacent pages on the printed sheet.

Another object of the invention is the provision 15 of a plate clamping or "lockup" mechanism having a novel plate clip operating device particularly designed and contrived to move axially with the said clip in such manner as to permit free access to the device between adjacent and/or oppositely positioned plates on a form cylinder, so that the 20 operator may actuate the device without the hindrance and inconvenience hitherto presented from the adjacent and overhanging bevelled edge of the adjoining plate.

It is also an object of the invention to provide 25 a plate lockup arrangement of generally improved construction, whereby the device will be simple, durable and inexpensive in construction, as well as convenient, practical, serviceable and efficient in its use.

30 With the foregoing and other objects in view, which will appear as the description proceeds, the invention resides in the combination and arrangement of parts, and in the details of construction hereinafter described and claimed.

35 The preferred embodiment of the invention is illustrated in the accompanying drawing, wherein:

Figure 1 is a top plan view of the invention as applied to a form cylinder, shown fragmentarily, 40 the plate clips being in operative, plate clamping position;

Figure 2 is an end elevational view, partly in section, as seen in the direction of the arrow 2 of Figure 1; and

45 Figure 3 is a transverse view taken on the line and as seen in the direction of the arrow 3 of Figure 1, the operating means for the plate clips being locked to prevent loosening of the clip from the printing plate.

50 In the several views of the preferred form of the invention, 11 designates generally a plate cylinder whereon is detachably mounted a plurality of half rings or semi-circular segments 11', each provided with a longitudinally extending recess or opening 12 wherein a plate clip 13 is slid-

ably arranged. The clip 13 is formed with laterally extending notches which receive inwardly directed projections or shoulders 14, 15 provided on the opposite walls of each groove, the said projections serving as ways to slidably support 5 the clips. The upper surface of each clip 13 is undercut to provide a lip 16, which is adapted to operatively engage the bevelled edge of a printing plate. Each of the clips 13, in the form shown by way of example in Figure 1, which are 10 arranged adjacent the center of the cylinder and adapted to be moved in opposite directions to engage and disengage their respective plates P, P', is provided with a threaded bore which receives a screw shaft 17 having a squared portion 20 where- 15 on a manipulating toothed wheel 18 is slidably mounted, it being understood that other clip assemblies similar to that shown may be provided elsewhere on the cylinder in the customary positions for coaction with other printing plates (not 20 shown). The squared portion 20 of the shaft 17 has a reduced and rounded end or gudgeon 19 rotatably received in a tapped hole or pocket formed in a block or abutment 21 fastened in any suitable manner as by screws 22 to the bottom of the 25 groove 12, the screws 22 also serving to secure each half ring 11' to the body portion of the cylinder 11. The shaft 17 is also provided with an annular shoulder 23 which abuts against an adjacent portion of the block 21, while the inner end 30 of the said shaft is engaged against a wall of the recess 12, so that its longitudinal movement is prevented.

As an additional feature of the present invention, a resilient pawl or dog 25, detachably secured by screws 26 to the bottom of each clip 13, is provided, the said dog having an upwardly extending finger or projection 27 adapted to retain the toothed wheel 18 in juxtaposition to the head of the clip 13, the dog 25 also serving to prevent 40 rotation of the said wheel when the clip is clampingly engaged with a printing plate in order to prevent accidental disengagement of the latter from the cylinder 11.

The function and general manner of operation of the device, in large measure indicated above, may be summarized as follows:

Assuming a printing plate P or P' has been placed on the cylinder in the usual manner, the clip adjacent thereto will be moved into clamp- 50 ing engagement with same by rotating the toothed wheel 18, the wheel being preferably actuated by a suitable operating tool (not shown) having for example, a gear segment to engage the teeth of the wheel 18. As the plate clip moves either into 55

or out of engagement with the printing plate, the toothed wheel 18 will be maintained against translational movement and in the same position relatively to the said clip by the finger 27 so that 5 the operator may conveniently apply the operating tool or ratchet member to the wheel 18 as the latter and the clip 13 move axially along the screw shaft. By further inspection of Figure 3, it will be understood that when a clip is disengaged from its adjacent plate and further moved in an axial direction to the limit of the space provided in the groove 12, the finger 27 will abut against the block 21 thereby preventing further movement of the wheel while still permitting the application of the operating tool thereto.

Various sizes of printing plates, it will be understood, may be accommodated on the cylinder 11 by adjusting the clip 13 to the extent required. 10 In conventional plate clamping apparatus where clip operating mechanism is provided between adjacent plates, the said operating mechanism is located constantly and inconveniently adjacent and partially under the overhanging edge of the 15 adjacent printing plate so that manipulation of the mechanism is at all times made awkward and inconvenient. In the instant device, on the contrary and by reason of the fact that the manipulating means moves with the clip, the said manipulating means or wheel 18 for the greater part 20 of its axial movement and particularly when effective to operatively engage the clip with the printing plate, is so located in the space between the edge of the adjacent printing plate and the 25 clip 16 as to permit an unimpeded application of the operating tool to the wheel 18. It will be noted that only at those times when the operating wheel 18 is carried axially to the limit of its outer travel, will a portion of its rim be found under the edge of the adjacent printing plate and then only at a time when no working pressure is required. A partial rotation of the wheel in this last mentioned position will move the rim of same into the open space alluded to above. When the 30 clip 13 is substantially in the plate clamping position indicated in full lines in Figure 3, the wheel 18 is locked by the pawl against rotation, thereby preventing accidental release of the printing plate. When the shaft 17 is turned in a clockwise direction by the wheel 18, the latter will be slid on the squared portion 20 of the shaft in a direction from left to right by the movement of the clip in withdrawing from the adjacent printing plate, the said wheel in the completely released 35 position of the plate being thrust or slid on the shaft by the clip into a position where the finger will be juxtaposed against or abut against the block 21.

As shown in Figure 1, it will be noted that a 40 pair of plate clips of the form embodying the present invention, are provided at a position which may be adjacent to the center of the cylinder, but it will be understood, of course, that the mechanism described and illustrated lends itself equally to the incorporation of similar plate clips at other portions of the cylinder, and wherever an individual plate clamping mechanism is necessary and/or desirable. When desired, any of the half rings or segments 11' containing the clip assemblies may be conveniently removed from the cylinder 11 by unfastening the screws 22, after which any individual clip may be removed from its respective segment.

It will be understood that the invention may 45 be embodied in other specific forms without de-

parting from the spirit or essential attributes thereof, and it is therefore desired that the present embodiment be considered in all respects as illustrative and not restrictive, reference being had to the claims rather than to the foregoing 5 description to indicate the scope of the invention.

1. In a device of the character described, the combination with a cylinder having a recess and adapted to receive a printing plate, a plate engaging clip arranged in said recess, said clip having a threaded bore, a screw shaft engaged in said bore and having an unthreaded portion, a toothed operating wheel slidably and non-rotatably mounted on the unthreaded portion, a pawl fastened to the clip and engageable with the toothed wheel, and other means including an abutment secured to the cylinder for preventing axial movement of the shaft relatively to the cylinder, said pawl serving to retain the operating wheel against 10 translational movement relatively to the clip.

2. In a clamping mechanism for securing a printing plate to a form cylinder having a recess, a plate clip slidable in the recess, a member having a screw threaded portion thereon and an unthreaded portion, said clip being connected to said threaded portion, an abutment removably secured in the recess, a gudgeon formed on the member and rotatably arranged in the abutment, a manually operable member slidably movable on 15 the unthreaded portion of the member, and a device for locking the manually operable member against rotation and for preventing axial movement of same relatively to the clip.

3. In a device of the character described, the combination with a plate cylinder, of means removably secured to said cylinder and having a recess, a plate engaging clip slidably mounted in the recess, other means integrally formed in the first mentioned means for guiding the clip in the 20 recess, threaded means connected to said clip for moving same, a member moving with the clip for operating the threaded means, and an abutment rotatably receiving the threaded means at one end, said threaded means having its other end 25 engaged against a second abutment, said last mentioned abutment being provided on the said cylinder.

4. In a device of the character described, the combination with a cylinder adapted to have a 30 printing plate operatively secured thereto, means securable to the cylinder and having a recess, a plate clip slidably arranged in said recess, instrumentalities integrally formed in said cylinder for retaining said clip slidably supported in 35 the recess, a member rotatably engaged with said clip for moving same in a direction parallel with the axis of the cylinder, other means for preventing longitudinal movement of the member relatively to the cylinder, manually operable 40 means slidably and non-rotatably mounted on the member for turning the same to move the clip into and out of engagement with the plate, and a pawl secured to the clip, said pawl serving to prevent rotation of the manually operable means 45 and consequently of the member when the clip is operatively engaged with a plate, and to restrain the said member against translational movement relatively to the clip when the latter is moved.

5. In a device of the character described, the combination with a form cylinder having a recess and adapted to receive a printing plate, of a plate engaging clip slidably supported in the recess, means threadedly engaged in the clip for moving same in a direction parallel to the axis of 50

- the cylinder to engage and disengage a printing plate arranged on the said cylinder, said means having a rectilinear portion, a toothed wheel slidable but non-rotatably mounted on the rectilinear portion, and a pawl detachably secured to the clip and operatively engageable with the toothed wheel for locking same against rotation when the plate clip is clampingly engaged with the printing plate and for retaining the wheel against translational movement relatively to the clip.
5. In a clamping mechanism for securing a printing plate to a form cylinder having a recess, a plate clip slidable in ways formed in the recess, a member having a screw threaded portion thereon and an unthreaded portion, an abutment secured in the recess, said abutment rotatably supporting the member at one end, a manually operable element axially movable on the unthreaded portion of the member, and means secured to the clip for retaining the element against translational movement relatively to the clip.
10. In a clamping mechanism for securing a printing plate to a form cylinder having a recess, a plate clip slidable in ways formed in the recess, a member having a screw threaded portion thereon and an unthreaded portion, an abutment secured in the recess, said abutment rotatably supporting the member at one end, a manually operable element axially movable on the unthreaded portion of the member, and means secured to the clip for retaining the element against translational movement relatively to the clip.
15. In a clamping mechanism for securing a printing plate to a form cylinder having a recess, a clamp member having a screw thread with an axis parallel to the cylinder axis, a threaded element engaging the said screw thread and rotatably supported in the recess and held against axial movement, and an operating member se-
20. In a clamping mechanism for securing a printing plate to a form cylinder having a recess, a clamp member having a screw thread with an axis parallel to the cylinder axis, a threaded element engaging the said screw thread and rotatably supported in the recess and held against axial movement, and an operating member se-
25. In a clamping mechanism for securing a printing plate to a form cylinder having a recess, a clamp member having a screw thread with an axis parallel to the cylinder axis, a threaded element engaging the said screw thread and rotatably supported in the recess and held against axial movement, and an operating member se-

cured to the clamp member but rotatable with respect thereto; said operating member being arranged to rotate the threaded element but being movable axially with respect thereto.

8. In a clamping mechanism for securing a printing plate to a form cylinder having a recess, a clamp member having a threaded aperture with an axis parallel to the cylinder axis, a rotatably supported screw member engaging the threaded aperture and having an unthreaded portion and held in the recess against axial movement, and an operating wheel slidable axially on the unthreaded portion of the screw member but prevented from rotational movement with respect thereto; said operating wheel normally being held against axial motion with respect to the clamp member.

9. In a mechanism of the character described for securing a printing plate to a form cylinder having a recess, a clamp member having a screw thread with an axis parallel to the cylinder axis, an operating member secured to the clamp member but rotatable with respect thereto, and a rotatably supported element in the recess having a threaded portion engaging the screw thread and a prism portion on which the operating member is 25 slidably and non-rotatably fitted.

FREDERICK LAMATSCH.
